INVENTOR
SADIE Bosky

BY

Joseph H. Rose
HER ATTORNEY

UNITED STATES PATENT OFFICE.

SADIE BOSKY, OF BROOKLYN, NEW YORK.

BRASSIÈRE.

1,391,936.

Specification of Letters Patent. Patented Sept. 27, 1921.

Application filed February 27, 1919, Serial No. 279,658. Renewed August 16, 1921. Serial No. 492,874.

To all whom it may concern:

Be it known that I, SADIE BOSKY, of 1512 Union street, Brooklyn, New York, a citizen of the United States of America, have 5 invented certain new and useful Improvements in Brassières, of which the following is a specification.

This invention relates to an article of feminine wearing apparel commonly known 10 as a brassière. As generally used, the brassière is worn over but above the corset for the purpose of confining and supporting the breasts and is for that reason a tight fitting garment. With the lowering of the 15 corsets as decreed by modern fashion, the usefulness of the brassière has steadily increased. Large breasted women have found, however, that the brassière as now constructed does not materially reduce the size 20 of the bust, but merely gives a neater appearance.

The main object of the invention is to construct an undergarment of this character which will not only give the wearer a 25 trim appearance but will materially reduce the apparent size of the bust by effecting a flattened appearance so desired by the average woman in place of the pronounced forward projection of the breasts common to 30 large breasted women. A further object of the invention is an improvement in the construction of brassières whereby the same may be more loosely worn and more ornately decorated, thereby eliminating the 35 necessity for other undergarments such as corset covers, camisoles and the like.

Referring to the drawings in which what are now considered the preferred forms of the invention are now shown:

40 Figure 1 is a rear elevation of a brassière laid out flat.

Fig. 2 is a diagram showing the manner in which the brassière is worn.

Fig. 3 is a section taken on line 3—3 of 45 Fig. 1 showing the construction of a pocket.

Fig. 4 is a view similar to Fig. 1 of a modified form of the invention which is in some respects preferable to the form shown in Fig. 1.

50 The brassière 1 may be constructed of any suitable material such as silk, satin, or cotton goods and is preferably formed with the usual top and bottom hems 2 and 3 with the opening preferably in the back. Any 55 form of fastening such as hooks 4 and eyes

5 may be used for fastening the garment around the wearer. Shoulder straps 6 and 7 may be sewed to the top hem 2 to suspend the garment from the shoulders. Darts 17 and 17' may also be provided under the 60 arms for fitting the garment to the form of the wearer. Secured to the under side of the garment are a pair of pockets 8 and 9. The pockets are equi-distant from the longitudinal center of the garment with the 65 tops 10 thereof preferably below the top 11 of the brassière. Preferably the pockets taper toward the bottom. The pockets are for the purpose and are designed to receive and confine the pendant breasts 12 of the 70 wearer, the pockets serving to separate the breasts and to draw them to either side of the chest thus effecting a flattened appearance and reducing the apparent size of the bust. The pockets may be formed of the 75 same material as the brassière itself and may be stitched thereto on the two sides and bottom in the usual manner with a hem 13 at the top.

In order to assist or further accentuate the 80 drawing of the breasts to either side, I may design the pockets 8' and 9' (Fig. 4) for a brassière 1' with downwardly divergent inner edges 14 and 15. The angle of divergence may of course be varied to suit the 85 individual requirements of the wearer being preferably greater for women with larger breasts.

The manner of use of my invention will be at once apparent from the foregoing description. The brassière is fitted around the wearer in the usual manner but care is taken to see that the pendant breasts are confined within the pockets. By employing pockets or equivalent means it will at once be apparent that the brassière itself need not be made as tight fitting as an ordinary garment of this character and that, therefore, it may be worn without an overgarment such as a 90 corset cover or camisole.

100 In accordance with the provisions of the patent statutes, I have herein described the principle of operation of my invention, together with the apparatus, which I now consider to represent the best embodiment 105 thereof, but I desire to have it understood that the apparatus shown is only illustrative and that the invention can be carried out by other means. Also, while it is designed to use the various features and elements in the 110

combination and relations described, some of these may be altered and others omitted without interfering with the more general results outlined, and the invention extends to such use.

Having described my invention, what I claim and desire to secure by Letters Patent is:

1. As an article of wearing apparel, a brassière comprising a strip of material, a pair of spaced pockets secured to the under side of said material on either side of and adjacent the middle portion thereof, and sep-

arable means for closing said brassière at the back of the wearer, said pockets being so positioned as to draw the breasts around and away from the middle of the chest, when the brassière is fastened around the wearer.

2. A brassière as claimed in claim 1 in which the adjacent inner walls of the pockets are downwardly divergent for the purpose set forth.

In testimony whereof I have affixed my signature.

SADIE BOSKY.
